CHEMICAL FEEDER FOR FEEDING CHEMICALS INTO WATER SUPPLY SYSTEMS

Earl C. Reynolds, Detroit, Mich.

Application April 29, 1949, Serial No. 2,331

Term of patent 14 years

(Cl. D16—2)

To all whom it may concern:

Be it known that I, Earl C. Reynolds, a citizen of the United States, residing at Detroit, in the county of Wayne and State of Michigan, have invented a new, original, and ornamental Design for Chemical Feeders for Feeding Chemicals into Water Supply Systems, of which the following is a specification, reference being had to the accompanying drawing, forming a part thereof, in which:

Fig. 1 is a front elevational view of a chemical feeder for feeding chemicals into water supply systems embodying my new design;

Fig. 2 is an elevational view taken from the left of Fig. 1;

Fig. 3 is a top plan view thereof; and
Fig. 4 is a bottom plan view thereof.

I claim:

The ornamental design for a chemical feeder for feeding chemicals into water supply systems, substantially as shown.

EARL C. REYNOLDS.
